UNITED STATES PATENT OFFICE.

CARL HANS BRUNOW, OF NEW YORK, N. Y.

DESIGN FOR A CORN OR FRUIT HOLDER.

48,305.

Specification for Design.

Patented Dec. 21, 1915.

Application filed August 20, 1915. Serial No. 46,561. Term of patent 3½ years.

To all whom it may concern:

Be it known that I, CARL H. BRUNOW, a subject of the Emperor of Germany, residing in the borough of Manhattan, city, county, and State of New York, have invented a new, original, and ornamental Design for a Corn or Fruit Holder, of which the following is a specification, reference being had to the accompanying drawing, forming part thereof.

I claim:

The ornamental design for a corn or fruit holder, as shown.

In testimony whereof I have hereunto signed my name.

CARL HANS BRUNOW.
